PIPETTE

Waddy T. Mathis, Hamden, Conn., assignor to
Clay Adams Co. Inc., New York, N. Y., a corpora-
tion of New York

Application May 27, 1941, Serial No. 395,332

18 Claims. (Cl. 222—192)

This invention relates generally to pipettes and similar laboratory apparatus of the type employed for collecting, transferring or dispensing liquids.

It is well known that in using pipettes for collecting, transferring or dispensing liquids, the customary practice has been to draw the liquid into the pipette by means of suction created by the mouth and after withdrawing the tube from the mouth to hold such liquid in the pipette by sealing the top end of the tube by the thumb or finger.

Thereafter the transferring or dispensing of the liquid was controlled by the pressure of the thumb or finger.

The above described customary practice possesses inherent disadvantages among which are the following. Since the liquids, in connection with which the pipettes are used are often of a poisonous or otherwise injurious nature this practice of sucking in liquids is fraught with great danger because the liquid is apt to be inadvertently drawn into the mouth of the user. Also the above described manner of finger control is efficient and sensitive only when practiced by one highly skilled in its technique.

It is therefore one of the principal objects of my invention to provide a device for use with a pipette in which a suction for drawing in liquids is obtained without any danger to the user and in which at the same time novel means for sensitively and efficiently controlling the transferring or dispensing of the liquid is provided.

Another object of my invention is to provide a device of the class described in which pipettes of relatively large size may be automatically filled to capacity by the use of a suction bulb of relatively small size.

Other objects of my invention will become apparent in the following detailed description thereof.

In the accompanying drawing, in which is shown one of the various possible embodiments of my invention,

Fig. 1 is a side elevational view, partly in section, of a pipette and device therefor, constructed in accordance with my invention;

Fig. 2 is a front elevational view of a portion thereof;

Fig. 3 is a vertical sectional view of a portion of the device and pipette shown in Fig. 1; and

Fig. 4 is a view similar to Fig. 2 but with the suction bulb removed.

Referring now in detail to the drawing, I have shown a pipette or tube 10 of the type customarily employed in laboratory work for collecting, trans-

ferring and dispensing fluids and provided with suitable graduations 11 for measuring the quantity of fluid drawn into the tube 10.

For creating a suction for the purpose of drawing fluid into the tube, without danger to the user, I employ a collapsible rubber bulb 12. The said bulb 12 is made with a thickened bottom wall portion 12a provided with an aperture 14 communicating with the hollow interior of the bulb 12. The suction bulb 12 is supported on a frame 15 comprising a base portion 15a and a wall 15b upstanding therefrom. It is noted that the inner surface 16 of the wall 15b of the frame 15 is concaved to conform to the shape of the bulb 12 and forms an abutting surface against which the bulb 12 may be pressed to collapse the same. Projecting outwardly from the outer surface of the wall 15b, is a hook shaped finger holding member 17. A nipple member 18 threadedly received in the frame base 15a and having an upwardly projecting tapered portion 18a, frictionally passing through the aperture 14, serves to hold the bulb 12 in effective position.

The said nipple portion 18a terminates in an angularly bent portion 20, inclined in a direction away from the frame wall 15b, and is further provided with a flattened end 21. The purpose and function of the nipple portion 20 and end 21 will soon become apparent as the description proceeds. The frame base 15a is provided with an opening 23 extending inwardly from the bottom surface thereof. A resilient lining member 24, in the said opening 23 frictionally receives the upper open end of the tube 10 therein, as clearly shown in Fig. 3 of the drawing. An aperture 25 in the frame base 15a, communicating with the opening 23, and in turn communicating with an aperture 26 extending through the nipple 18 completes the air pasageway from the hollow interior of the bulb 12 to the interior of the tube 10.

In accordance with my invention I have provided the following sensitive control means, preferably located wholly within the bulb, and so constructed and arranged that when the bulb 12 is collapsed or compressed, air therefrom will be exhausted through the tube 10, or through an opening 30 in the wall of the said bulb 12, or through both, and upon release of said bulb from compressed position, air may be drawn up through said tube 10 to fill the same with liquid.

Frictionally received on the nipple portions 20 and 21 is an air valve or control tube 31 made of suitable flexible material, such as for example rubber. When the bulb 12 is in its normal non-

compressed position, the air tube 31 is open, the tube being preferably of such length that it will lie adjacent the wall of the bulb 12, as in Fig. 1.

In view of the above construction, the manner of use of my novel and improved pipette apparatus will now be described.

The portion 17 of the pipette device is hooked over the hand of the user with the thumb encircling the bulb 12 and with a finger overlying the opening 30. If it is desired to draw fluid into the tube 10, the bulb 12 is compressed against the frame wall 15b. In view of the construction and arrangement of the angular nipple portion 20 after only a limited amount of compression of the bulb 12, the tube 31 will be clinched against the flattened end 21 to shut off the air passageway leading from the tube 10 to the interior of the said bulb 12. During this compressing operation the opening 30 is left uncovered so that the air within the bulb 12 may be expelled therethrough. After the bulb 12 has been fully compressed the opening 30 is covered by the thumb or finger and the compression of the bulb released. As soon as the said bulb 12 has been restored sufficiently to straighten out the kink in the air tube 31, fluid will be drawn into the tube 10 by the suction created within the bulb 12, and held therein as long as the opening 30 remains covered, or by the closed air tube 31 if the tube is sealed by being clinched against the nipple portion 21.

In view of the above described operation of my invention it is noted that if the tube 10 were of such size that a single complete compression and release of the bulb 12 would not fill the tube 10 to a sufficient height, the said tube 10 may be further filled by a second or third compression of the bulb 12 with a minimum of loss of the fluid already in the tube due to compression of the bulb. At the commencement of each such compression of the bulb, the air tube 31 is simultaneously and automatically actuated to close the air passageway, to retain the fluid already in the pipette. After the air passage is so sealed, the opening 30 is uncovered, and further compression expels the air from the bulb. Opening 30 is now again covered, and as the compression of the bulb is released, the air tube 31 straightens out, opening the passageway from the bulb to pipette 10, so that additional fluid may be drawn up.

After a desired amount of fluid has been drawn into the tube 10 by the method above described, sensitive dispensing control may be exercised by regulating the amount of pressure applied to the bulb 12 in the area of the tube 31 and nipple portion, while covering the opening 30, to force the fluid out of the tube 10.

Also, if desired, a gravity control may be exercised by uncovering the opening 30 and clinching the tube 31 to shut off the air passageway to the tube 10. Thereafter, slight release of pressure on the clinched tube 31 will open the air passageway to permit gravity flow of the fluid from the tube 10, the amount of flow ranging from a drop to a stream, depending upon the amount of pressure of the tube 31 against the nipple portion 21.

To facilitate the above described dispensing control action any suitable device may be provided on the outer surface of the bulb 12 to indicate where effective pressure is to be applied. In the drawing I have shown one such indicating device in the form of an annular ridge 40.

It will thus be seen that there is provided a device in which the several objects of this invention

are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having described my invention, I claim as new and desire to secure by Letters Patent:

1. In a laboratory apparatus of the class described, the combination of a tube, a suction bulb having a bottom aperture, means for interconnecting said bulb with said tube whereby a suction may be created in said tube upon compressing and releasing said bulb, said last named means comprising a nipple member frictionally received in said bulb aperture and having a portion thereof projecting into the hollow interior of said bulb, said member having an opening therethrough adapted to communicate with the hollow interior of said bulb and with said tube, and a flexible tubular member within said bulb received on said projecting portion of said nipple to form a continuation of the air passageway from said tube to the interior of said bulb, said tubular member being adapted to be clinched up against said nipple portion upon compression of said bulb so that passage of air between said tube and said bulb may be shut off or otherwise controlled.

2. In a laboratory apparatus of the class described, the combination according to claim 1 in which the suction bulb is provided with a second aperture adapted to be covered or uncovered by the thumb or finger of the user to obtain added flow control.

3. In a laboratory apparatus of the class described, the combination according to claim 1 in which the said projecting portion of said nipple member terminates in a flattened end to facilitate the said clinching action of said flexible tubular member thereagainst.

4. In a laboratory apparatus of the class described, the combination according to claim 1 in which the said projecting portion of said nipple member is angularly disposed in a direction toward the wall of said bulb so that the free end of said flexible tubular member will lie adjacent the said wall of said bulb.

5. In a laboratory apparatus of the class described, the combination according to claim 1 in which the said projecting portion of said nipple member is angularly disposed in a direction toward the wall of said bulb so that the free end of said flexible tubular member will lie adjacent the said wall of said bulb, said angularly disposed portion of said nipple member terminating in a flattened end to facilitate the clinching action of said flexible tubular member thereagainst.

6. In a laboratory apparatus of the class described, the combination according to claim 1 in which the said projecting portion of said nipple member terminates in a flattened end to facilitate the said clinching action of said flexible tubular member thereagainst, said suction bulb being provided with a second aperture adapted to be covered or uncovered by the thumb or finger of the user to obtain added flow control.

7. In a laboratory apparatus of the class described, the combination according to claim 1 in which the said projecting portion of said nipple member is angularly disposed in a direction toward the wall of said bulb so that the free end

of said flexible tubular member will lie adjacent the said wall of said bulb, said suction bulb being provided with a second aperture to be covered or uncovered by the thumb or finger of the user to obtain added flow control.

8. In a laboratory apparatus of the class described, the combination according to claim 1 in which the said projecting portion of said nipple member is angularly disposed in a direction toward the wall of said bulb so that the free ends of said flexible tubular member will lie adjacent the said wall of said bulb, said angularly disposed portion of said apertured member terminating in a flattened end to facilitate the clinching action of said flexible tubular member thereagainst, said suction bulb being provided with a second aperture adapted to be covered or uncovered by the thumb or finger of the user to obtain added flow control.

9. In a laboratory apparatus of the class described, the combination of a tube, a suction bulb having a bottom aperture, means for interconnecting said bulb with said tube whereby a suction may be created in said tube upon compressing and releasing said bulb, said last named means comprising a frame having a base portion and a rigid wall upstanding therefrom adapted to serve as an abutment against which the said bulb is compressed, a nipple member mounted on said frame and having a portion thereof received in said bottom aperture of said bulb, said nipple member having a portion thereof projecting into the hollow interior of said bulb and a flexible tubular member within said bulb received on said projecting portion of said nipple, said flexible tubular member being adapted to be clinched up against said projecting nipple portion upon compression of said bulb.

10. In a laboratory apparatus of the class described, the combination according to claim 1 in which the said projecting portion of said apertured member terminates in a flattened end portion to facilitate the said clinching action of said flexible tubular member thereagainst, said suction bulb being provided with a second aperture adapted to be covered or uncovered by the thumb or finger of the user to obtain added flow control and means on the outer surface of said bulb to indicate where the said bulb is to be compressed to facilitate the said clinching action of said flexible tube.

11. In a laboratory apparatus of the class described, the combination according to claim 9 in which said suction bulb is provided with a second aperture adapted to be covered or uncovered by the thumb or finger of the user to obtain added flow control.

12. In a laboratory apparatus of the class described, the combination according to claim 9 in which said suction bulb is provided with a second aperture adapted to be covered or uncovered by the thumb or finger of the user to obtain added flow control and means on the outer surface of said bulb to indicate where the said bulb is to be

compressed to facilitate the said clinching action of said flexible tube.

13. In a laboratory apparatus of the class described, the combination according to claim 9 in which the said frame is provided with a hook shaped holding member to facilitate the use of said apparatus.

14. In combination, a measuring tube, a suction bulb interconnected with said measuring tube, a flexible air controlling tube within said suction bulb and interconnected with said measuring tube, said flexible air controlling tube being actuated by the side wall of said bulb as the bulb is compressed and released in producing the suction effect.

15. In combination, a measuring tube, a suction bulb interconnected with said measuring tube, a flexible air controlling tube within said suction bulb and interconnected with said measuring tube, one end of said air controlling tube being in contact with the inner walls of said bulb, whereby the air passageway through said controlling tube is automatically varied as the bulb is compressed and released in producing the suction effect.

16. In combination, a measuring tube, a suction bulb, a nipple member interconnecting said measuring tube with said bulb, a flexible air controlling tube disposed within said bulb and interconnected with said measuring tube, a portion of said flexible tube being disposed adjacent the wall of said bulb whereby the air passageway through said flexible tube is automatically varied as the bulb is compressed or released in producing the suction effect.

17. In combination, a measuring tube, a suction bulb, a nipple member interconnecting said measuring tube with said bulb, a flexible air controlling tube disposed within said bulb and interconnected with said measuring tube a portion of said flexible tube being disposed adjacent the wall of said bulb whereby the air passageway through said flexible tube is automatically varied as the bulb is compressed or released in producing the suction effect, and a frame associated with said nipple member, said frame having a rigid wall adapted to serve as an abutment against which the bulb is compressed.

18. In combination, a measuring tube, a suction bulb, a nipple member interconnecting said measuring tube with said bulb, a flexible air controlling tube disposed within said bulb and interconnected with said measuring tube, a portion of said flexible tube being disposed adjacent the wall of said bulb whereby the air passageway through said flexible tube is automatically varied as the bulb is compressed or released in producing the suction effect, and a frame associated with said nipple member, said frame having a rigid wall adapted to serve as an abutment against which the bulb is compressed, said frame being provided with a hook shaped holding member to facilitate the use of said apparatus.

WADDY T. MATHIS.
